United States Patent Office

Des. 210,837

Patented Apr. 23, 1968

210,837

GOLF TEE

Daniel S. Warner, 16010 37th NE.,
Seattle, Wash. 98155

Filed July 29, 1966, Ser. No. 3,254

Term of patent 14 years

(Cl. D34—5)

FIG. 1

FIG. 2

FIG. 3

FIG. 4

FIG. 5

FIG. 1 is a perspective view of a golf tee showing my new design;

FIG. 2 is a front elevational view of the golf tee;

FIG. 3 is an enlarged fragmentary vertical sectional view taken as indicated by line 3—3 in FIG. 1;

FIG. 4 is an enlarged horizontal sectional view taken along the line 4—4 of FIG. 2; and

FIG. 5 is a top plan view to an enlarged scale.

I claim:

The ornamental design for a golf tee, as shown.
